UNITED STATES PATENT OFFICE.

JOSEPH A. COSTELLO, OF CLEVELAND, OHIO, ASSIGNOR TO CLEVELAND CAR SPECIALTY COMPANY, OF CLEVELAND, OHIO, A CORPORATION OF WEST VIRGINIA.

CARLINE.

1,314,573.

Specification of Letters Patent. Patented Sept. 2, 1919.

Application filed June 19, 1918. Serial No. 240,729.

To all whom it may concern:

Be it known that I, JOSEPH A. COSTELLO, a citizen of the United States, residing at Cleveland, in the county of Cuyahoga and

5 State of Ohio, have invented a new and useful Carline, of which the following is a specification.

This invention relates to improvements in metal carlines suitable for use in the construction of car-roofs, and pertains more especially to a strong and inexpensive pressed steel carline which is well adapted for use as one of the transverse members of a car-roof-frame comprising two laterally 10 spaced metal side plates adapted to be braced apart and tied together by carlines embodying my invention and can be readily pressed at one operation by means of dies from a single oblong steel plate or sheet of 15 suitable dimensions and applied with facility to the hereinbefore mentioned side plates.

The primary object of this invention is not only to produce a carline of the character 20 indicated which comprises a body in the form of a trough adapted to be interposed endwise between said side plates and has two plate-forming members formed at opposite ends respectively of the carline and 25 rigid with the trough-shaped body and arranged to extend under and adapted to be attached to said side plates, but to form a strong connection between said trough-shaped body and said plate-forming members 30 centrally between the side edges of said plate-forming members and more especially to render the carline strong and durable in its end portions.

With this object in view, and to the end 35 of attaining any other object hereinafter appearing, this invention consists in such peculiarity in the contour of said end portions of the carline and in such combinations and relative arrangement of the parts as are 40 hereinafter described in this specification, pointed out in the claims, and illustrated in the accompanying drawings.

In said drawings, Figure 1 is a top plan 45 of a carline embodying my invention and shows the carline applied to the side plates of a car-roof-frame, but the central portion of the carline is broken away to reduce the size of the drawing. Fig. 2 is a vertical section taken along the line 2—2, Fig. 1. Figs. 1 50 and 2 are drawn on the same scale. Figs. 3, 4

and 5 are vertical sections taken along the lines 3—3, 4—4, and 5—5, respectively, Fig. 2, and are drawn on a larger scale than Figs. 1 and 2.

My improved carline is adapted especially 60 for use in the construction of a car-roof-frame comprising two laterally spaced substantially horizontal and substantially parallel metal side plates each of which preferably consists of a Z-bar arranged with 65 its web or body-portion A substantially horizontal and with its upper flange a arranged at the inner side of the side plate formed by said bar. Each side plate is therefore shown as comprising a substantially 70 horizontally arranged body-portion A extending longitudinally of the side plate and a member a which projects upwardly from said body-portion at the inner side and extends longitudinally of the side plate. 75

The side plates are adapted to be tied together and braced apart by any suitable number of carlines embodying my invention, and are shown as connected together 80 by one of said carlines.

My improved carline comprises two substantially horizontal plate-forming members B arranged at opposite ends respectively of the carline at the bottom of the carline. In Figs. 1 and 2 one of the plate-forming members B is shown as overlapping the under side of the body-portion A of one of the side plates, and the other of said plate-forming members is shown overlapping the under side of the body-portion of 85 the other of said side plates. The carline is secured to the side plates as will hereinafter appear.

My improved carline also comprises a body which is in the form of a trough b 95 interposed endwise between the upwardly projecting members a of the side plates and connected at one end of its bottom to one of the plate-forming members B and connected at the other end of its bottom to the 100 other of said plate-forming members. The trough-shaped body b is rigid with the plate-forming members B.

The trough-shaped body b is shown provided at the top with two laterally and outwardly projecting flanges 12 arranged at opposite sides respectively and extending longitudinally and from end to end of said body. 105

At each end of the trough-shaped body 110

b are formed two upright abutment-members 13 for the inner side of the upwardly projecting member a of the adjacent side plate the under side of which is shown overlapped by the plate-forming member B adjacent said end of said body, and said abutment-members extend laterally of and outwardly from opposite sides respectively of and are rigid with said body and attached 10 to said member of said side plate as will hereinafter appear. Each plate-forming member B is offset downwardly, as at 14, centrally between its side edges and adjacent the body b, and the offset portion 14 of each 15 plate-forming member B is arranged therefore transversely of the body-portion A of the adjacent side plate and adjacent the space between the adjacent abutment-members 13 and has preferably such contour and 20 dimensions that it is substantially as wide as said space and forms a recess 15 which is deepest adjacent the inner side of and covered by said side plate and gradually reduced in depth toward the outer end of said 25 plate-forming member. Each plate-forming member B is shown riveted, as at 16, between its downwardly offset portion 14 and each side edge of said plate-forming member to the body-portion A of the adjacent side plate.

Each abutment-member 13 is riveted, as at 18, to the upwardly projecting flange a of the adjacent side plate, and it will be observed that each abutment-member 13 connects the adjacent flange 12 of the trough b with the adjacent plate-forming member B. Each end of the trough has a downward enlargement 19 arranged at the lower end of the space between the adjacent abutment-members, and the bottom of said enlargement slopes downwardly toward the downwardly offset portion 14 of the adjacent plate-forming member, and the bottom of the recess 15 formed by said offset portion 40 of said plate-forming member terminates in said bottom of said enlargement of the trough. A carline having its end portions contoured as hereinbefore described has great strength at the ends of the bottom of 45 the trough and can be pressed at one operation from a single plate or sheet of steel by simple and inexpensive dies or tools. Also, any water which results from sweating or condensation internally of said trough and 50 accumulates in the ends of the trough will gravitate into the recesses 15 formed at said ends and large enough in dimensions for the purpose, so that said water, instead of remaining until evaporated in contact with 55 opposing surfaces of the carline and side plates, is received by said recesses where its evaporation is facilitated while being held out of contact with the side plates. It will 60 be observed therefore that each downward enlargement 19 of the body of the carline 65

and the offset portion 14 of the adjacent plate-forming member B form not only a reinforcement but a basin arranged under the space between the adjacent abutment-members 13 and under the body-portion A 70 of the adjacent side plate.

What I claim is:—

1. In a metal carline, two spaced substantially horizontal plate-forming members, a trough-shaped body extending between and rigid with said plate-forming members and provided at the top with two laterally and outwardly projecting flanges arranged at opposite sides respectively and extending longitudinally and from end to end of said body, and two spaced abutment-members adjacent each plate-forming member and extending to said plate-forming member from said flanges, said abutment-members being spaced transversely of the carline, each end of the aforesaid body having a downward enlargement at the lower end of the space between the adjacent abutment-members, the bottom of said enlargement sloping downwardly toward the adjacent plate-forming member, and each plate-forming member being offset downwardly at the adjacent downward enlargement of the aforesaid body and having the bottom of its offset portion terminating in the bottom of said enlargement 95 of said body.

2. In a metal carline, two spaced substantially horizontal plate-forming members, a trough-shaped body extending between and rigid with said plate-forming members and provided at the top with two laterally and outwardly projecting flanges arranged at opposite sides respectively and extending longitudinally and from end to end of said body, and two spaced abutment-members adjacent each plate-forming member and extending to said plate-forming member from said flanges, said abutment-members being spaced transversely of the carline, each end of the aforesaid body having a downward enlargement at the lower end of the space between the adjacent abutment-members, each plate-forming member being offset downwardly at the adjacent downward enlargement of said body and having its offset portion terminating in said enlargement of said body, and the offset portion of each plate-forming member being substantially as wide as the aforesaid space.

3. In a metal carline, two spaced substantially horizontal plate-forming members, a trough-shaped body extending between and rigid with said plate-forming members and provided at the top with two laterally and outwardly projecting flanges arranged at opposite sides respectively and extending longitudinally and from end to end of said body, and two spaced abutment-members adjacent each plate-forming member and extending to said plate-forming member from 130

said flanges, said abutment-members being spaced transversely of the carline, each end of the aforesaid body having a downward enlargement at the lower end of the space 5 between the adjacent abutment-members, each plate-forming member being offset downwardly at the adjacent downward enlargement of said body, and the offset portion of each plate-forming member and the 10 adjacent downward enlargement of said body forming a basin arranged under said space.

4. The combination, with two laterally spaced side plates of a car-roof-frame, of 15 a metal carline comprising two substantially horizontal plate-forming members which extend under and are secured to opposite side plates respectively, which carline has a trough-shaped body extending between and 20 rigid with said plate-forming members of the carline and is provided adjacent each of said plate-forming members with two abutment-members arranged at the inner side and spaced longitudinally of and secured 25 to the adjacent side plate, each plate-forming member of the carline having a downwardly offset portion extending from under the space between the adjacent abutment-members in the direction of the outer 30 side of the adjacent side plate and forming a recess which is reduced in depth in said direction.

5. The combination, with two laterally spaced side plates of a car-roof-frame, of a 35 metal carline comprising two substantially horizontal plate-forming members which extend under and are secured to opposite side plates respectively, which carline has a trough-shaped body extending between and 40 rigid with said plate-forming members of the carline and is provided adjacent each of said plate-forming members with two abutment-members arranged at the inner side and spaced longitudinally of and secured 45 to the adjacent side plate, each end of said body having a downward enlargement at the

lower end of the space between the adjacent abutment-members, each plate-forming member of the carline being offset downwardly at the adjacent downward enlargement of said body and having the bottom of its offset portion terminating in the bottom of said enlargement of said body, and the offset portion of each plate-forming member of the carline being substantially as wide as the space between the adjacent abutment-members and extending outwardly from under said space and transversely of the adjacent side plate.

6. The combination, with two laterally spaced side plates of a car-roof-frame, of a metal carline comprising two substantially horizontal plate-forming members which extend under and are secured to opposite side plates respectively, which carline has a trough-shaped body extending between and rigid with said plate-forming members of the carline and is provided adjacent each of said plate-forming members with two abutment-members arranged at the inner side and spaced longitudinally of and secured to the adjacent side plate, each end of said body having a downward enlargement at the lower end of the space between the adjacent abutment-members, each plate-forming member of the carline being offset downwardly at the adjacent downward enlargement of said body, and the offset portion of each plate-forming member of the carline and the adjacent downward enlargement of said body forming a basin arranged under the space between the adjacent abutment-members and under the adjacent side plate.

In testimony whereof I sign the foregoing specification in the presence of two witnesses.

JOSEPH A. COSTELLO.
